Filed Oct. 28, 1957, Ser. No. 692,882

6 Claims. (Cl. 312—140.4)

This invention relates to furniture, and more particularly to partition structures for use with desks, tables, and the like to provide semi-private compartments or offices for various office functions.

There are many office functions, such as Purchasing, Sales, Interviewing, and the like, which require a lesser degree of privacy than is afforded by a completely enclosed office formed by permanent floor-to-ceiling walls or partitions. For functions of this sort, partitions mounted along the sides and rear of a desk can provide an adequate degree of privacy. Various partition installations for desks, tables, counters and the like have been suggested heretofore, but such installations have been bulky and expensive. Also, they usually require permanent anchoring, and they invariably deface or mar the articles of furniture to which they are applied.

The primary object of my invention is to provide an improved partition structure for various articles of furniture which will be free from the aforementioned and other difficulties inherent in partition structures known heretofore.

More particularly, it is an object of my invention to provide an improved partition structure which is suitable for use with such articles of furniture as desks, tables, benches, counters, and the like to provide semi-private compartments or offices, and which can be applied to, and removed from, such articles with great ease and in a minimum of time.

Another object of my invention is to provide an improved partition structure as aforesaid which is simple, yet very sturdy, in construction.

Still another object of my invention is to provide an improved partition structure as above set forth which will not mar or deface the furniture to which it is applied.

A further object of my invention is to provide an improved partition structure of the type indicated above which can be installed readily even by unskilled workmen.

It is also an object of my invention to provide an improved partition structure as aforesaid which can be fabricated and assembled easily, which is inexpensive in cost, which is pleasing in appearance, and which is highly efficient in use.

In accordance with one form of my invention, the structure comprises a plurality of substantially U-shaped clamps of spring steel or other resilient metal which can be slipped easily onto the overhanging marginal portions of the customary tops of desks, tables, etc. at spaced points therealong and held clamped thereon by the inherent resiliency of the clamps. Each clamp has an arm which rests on the desk or table top, these arms being arranged parallel to each other and at right angles to the edges of said marginal portions. Secured to these arms, as by spot welding, is a channel member or other suitable holder in which is mounted a partition of glass, plastic, wood, or any other suitable material. One such structure can be mounted along a side of a desk, for example (either left or right), and another along the rear edge thereof. This provides

2

an L-shaped partition structure which affords a certain degree of semi-privacy. The proximate, vertical edges of the two partitions may be joined together by a suitable connecting device to give added strength and firmness to the structure. If desired, side partitions may be mounted along both sides of the desk to provide a U-shaped structure which will give still greater privacy. However, if a number of desks provided with my improved partition structure are to be placed adjacent to each other, as in crowded areas, only the L-shaped structure need be used, and the desks can be disposed in various arrangements to afford the desired type and degree of privacy.

The novel features of my invention, both as to its organization and manner of use, as well as additional objects and advantages thereof, will be understood more readily from the following description, when read in connection with the accompanying drawings, in which

Fig. 1 is a perspective view of one form of partition structure according to my invention, the structure being shown applied to a desk (shown in phantom) by way of illustration.

Fig. 2 is a fragmentary sectional view taken along the line 2—2 of Fig. 1.

Fig. 3 is a view similar to Fig. 2 but showing a modified form of clamping device according to my invention.

Fig. 4 is a fragmentary, perspective, exploded view of one form of corner piece for connecting the proximate edge portions of a pair of cooperating partitions in accordance with my invention.

Fig. 5 is a fragmentary sectional view taken along the line 5—5 of Fig. 1, and

Figs. 6 to 12, inclusive, are diagrammatic views illustrating various desk arrangements for desks equipped with partition structures according to my invention, the desks being variously arranged to provide different types and degrees of privacy to suit different requirements.

Referring more particularly to Figs. 1 to 5, inclusive, there is shown a desk 1 which includes a top 3 having overhanging left and right marginal portions 5 and 7, respectively, a front overhanging marginal portion 9, and a rear overhanging marginal portion 11. Clamped to the marginal portion 5 in spaced relation to each other therealong are a pair of substantially U-shaped clamps 13. The clamps 13 may be made of spring steel bands or of other resilient material, suitably finished to provide a pleasing appearance. Three or more such clamps 13 may also be clamped to the rear marginal portion 11 of the desk top.

Each clamp 13 has a relatively long arm 15 which engages and preferably lies flat against the upper surface of the top 3, a relatively short arm 17 which engages the lower surface of the top 3, and a connecting arm 19 which engages the side edge or the rear edge of the desk, as the case may be. The clamps 13 can be readily slipped onto the appropriate marginal portions, and they can be removed therefrom just as easily. No special tools are required for this. Because of the inherent resiliency of the material of the clamps 13, the clamps will firmly grip or clamp the desk top once they are applied thereto. Preferably, the arm 17 has an inwardly turned end 21. By first applying each clamp at the end 21, it can be tilted easily into position by simply pivoting around this end. The inwardly turned end 21 also serves to slightly "bite" into the desk top and thus assure a firm grip of the clamp thereon.

Secured to upper arms 15, as by spot welding, is a channel member or other suitable partition holder 23 of metal lined with strips 25 of felt or the like. The strips 25 are of a length somewhat shorter than the desk marginal portions along which they are to be disposed, and they are perpendicular to the arms 15. Thus, when the clamps 13 are mounted on the desk top with their arms

15 substantially normal or perpendicular to one of the edges thereof, the channel member 23 secured thereto will be disposed substantially parallel to such edge.

Mounted in each channel 23 between the strips 25 thereof is a panel partition 27 of glass, plastic, wood, fiber board, or any other suitable material. The panels 27 are of a height to extend upwardly from the desk top a distance sufficient to provide necessary privacy. With one panel 27 disposed along one side of the desk (either the left or the right side, as desired) and the other panel 27 disposed along the rear of the desk, there is provided an L-shaped partition structure. If a third panel is mounted along the other side of the desk, there is provided a U-shaped partition structure which affords even greater privacy.

To give added strength and firmness to the partition structure, the proximate, vertical, marginal or edge portions 27a of the panels 27 are connected together by a vertically extending corner piece 29. The connecting device 29 comprises a pair of cooperating outer and inner panel clamping members 31 and 33, respectively. The outer member 31 has seats 31a which engage the outer surfaces of the panel marginal portions 27a, and the inner member 33 has laterally extending arms 33a which similarly engage the inner surfaces of the panel marginal portions 27a. The outer member 31 is also formed with a channel 35 in which the heads 36 of one or more internally threaded sleeves 37 are received. The inner member 33 carries a corresponding number of screws 39 which are threaded into the sleeves 37. When the screws are tightened, the clamping members 31 and 33 are drawn together to firmly clamp the panels 27 and lock them to each other. A closure 40 having spring fingers 41 which snap into the clamping members 31, 33 closes the upper end of these clamping members and provides a finish therefor.

The channel members 23 may be pre-cut to standard sizes to fit the articles of furniture to which they are applied and welded to a suitable number of spring clamps 13 as above described. To mount a partition structure such as that described heretofore, it is merely necessary to slip the clamps 13 with attached channel members or partition holders 23 onto the marginal portions of the article of furniture, insert panels 27 of proper length into the holders 23, and connect the panels to each other by means of the connecting device 29. To remove the partition structure, the reverse steps are followed. In either case, the operation can be performed easily in but a few minutes and without the need for any tools except a conventional screw driver for the screws 39.

In Fig. 3 is shown a modified form of clamp 13. This clamp has an extension 43 which engages the side 45 of the desk 1 to provide greater stability, if desired. The clamp 13 may be either resilient or not, as deemed best. In either case, additional firmness or stability may be provided by securing the clamp to the desk by means of a screw 47. However, this arrangement is preferably used only for permanent installations, although it can, of course, be used in any installation.

Furniture provided with partition structures such as described above can be arranged in various ways to afford different degrees of privacy. For example, two desks, one with a left side and the other with a right side partition structure, both L-shaped, can be placed end-to-end to jointly enclose the two desks at the sides and rear, as shown in Fig. 6. In Fig. 7, two such desk arrangements placed back to back are shown. A somewhat less private arrangement for four desks is provided when only two diagonally opposite desks have the L-shaped partition structures mounted thereon, as in Fig. 8.

Fig. 9 shows an arrangement of four separate desks, each with a right hand, L-shaped partition structure thereon, in closely adjacent relation and with a chair 49 at the open side. An arrangement of this sort is suitable for interviewing or for purchasing functions, for example.

In Fig. 10 is shown another arrangement of desks using L-shaped partition structures. Here, the two sets of end desks are arranged side to back so that the vertically disposed desks effectively have partitions along both sides as well as the back, while the horizontally disposed desks have partitions only along the back and one side. However, by arranging four desks in "pin-wheel" fashion, as in the center set of desks, all four will effectively have partitions along both sides and the back to provide a greater degree of privacy for all. Various other desk arrangements which are self-explanatory are shown in Figs. 11 and 12, and many other arrangements will, no doubt, readily suggest themselves.

From the foregoing description, it will be apparent that I have provided an improved partition structure which is simple in construction, which can be applied and removed easily, and which readily lends itself to efficient use with many articles of furniture. It is to be understood that the structure described above is only for the purpose of illustration. Hence, I desire that the foregoing shall be taken merely as exemplary and not in a limiting sense.

I claim as my invention:

1. A device for supporting a privacy affording partition on the top of an article of furniture having an overhanging marginal portion along an edge thereof, said device comprising at least one substantially U-shaped clamping member adapted to embrace said marginal portion, said clamping member including a first arm adapted to rest on said top and a second arm having an inwardly directed free end adapted to engage the lower surface of said marginal portion and about which said clamping member can be tilted for applying said clamping member to said marginal portion, said clamping member being adapted to be retained on said marginal portion by the pressure of said first and second arms thereagainst, and a channel member secured to said first arm in a position to overlie said first arm and also said marginal portion when said clamping member is applied to said marginal portion, said channel member being adapted to receive a partition therein of a height such as to afford a substantial degree of privacy for said top.

2. A device for supporting a privacy affording partition on the top of an article of furniture having a vertical wall below said top and an overhanging marginal portion along an edge of said top beyond said wall, said device comprising at least one substantially U-shaped clamping member adapted to embrace said marginal portion, said clamping member including a first arm adapted to rest on said top and a second arm adapted to engage the lower surface of said marginal portion, said second arm having a downward extension adapted to engage said wall, said clamping member being tiltable about the juncture of said second arm and said extension when said juncture is engaged with said marginal portion lower surface near said edge thereof for applying said clamping member to said marginal portion, said marginal portion being adapted to then be retained on said marginal portion by pressure of said first and second arms thereagainst, and a channel member secured to said first arm in a position to overlie said first arm and also said marginal portion when said clamping member is applied to said marginal portion, said channel member being adapted to receive a partition therein of a height such as to afford a substantial degree of privacy for said top.

3. A device for supporting a privacy affording partition on the top of an article of furniture having an overhanging marginal portion along an edge thereof, said device comprising a plurality of substantially U-shaped, resilient clamping members adapted to embrace said marginal portion in spaced relation therealong and to be held thereon against said edge by the inherent resilience thereof, said clamping members each including a first arm adapted to rest on said top and a second arm

having an inwardly directed free end adapted to engage the lower surface of said marginal portion and about which the respective said clamping members can be tilted for applying said clamping members to said marginal portion, and a channel member secured to each of said first arms in a position to overlie said first arms and also said marginal portion when said clamping members are applied to said marginal portion, said channel member being adapted to receive a partition therein of a height such as to afford a substantial degree of privacy for said top.

4. A device for supporting a privacy affording partition on the top of an article of furniture having an overhanging marginal portion along an edge thereof, said device comprising a plurality of substantially U-shaped, resilient clamping members adapted to embrace said marginal portion in spaced relation therealong and to be held thereon against said edge by the inherent resilience thereof, said clamping members each including a first arm adapted to rest on said top and a second arm having an inwardly directed free end adapted to engage the lower surface of said marginal portion and about which the respective said clamping members can be tilted for applying said clamping members to said marginal portion, and a channel member secured to each of said first arms in a position to overlie said first arms and also said marginal portion when said clamping members are applied to said marginal portion, said channel member being adapted to receive a partition therein of a height such as to afford a substantial degree of privacy for said top, said clamping members and said channel member being so related that, when said first arms are disposed on said top substantially normal to said edge, said channel member will be disposed substantially parallel to said edge and will extend along substantially the entire length of said marginal portion.

5. A privacy affording partition structure for an article of furniture having a top with an overhanging marginal portion along an edge thereof, said structure comprising a plurality of spaced, substantially U-shaped, resilient clamping members adapted to embrace said marginal portion at spaced points therealong and to be held thereon against said edge by the inherent resilience thereof, said clamping members each including a first arm adapted to rest on said top and a second arm having an inwardly directed free end adapted to engage the lower surface of said marginal portion and about which the respective said clamping members can be tilted for applying said clamping members to said marginal portion, a holding member secured to said first arms in a position to overlie

said first arms and also said marginal portion when said clamping members are applied to said marginal portion, and a partition mounted in said holding member, said partition extending upwardly from said holding member a distance sufficient to afford a substantial degree of privacy for said top.

6. A privacy affording partition structure for an article of furniture having a top with a first marginal portion along one edge thereof and a second marginal portion along a second edge thereof which is angularly related to said first edge and which meets said first edge at a corner of said article of furniture, said structure comprising a plurality of spaced, substantially U-shaped, resilient clamping members certain ones of which are adapted to embrace said first marginal portion at spaced points therealong and certain others of which are adapted to embrace said second marginal portion at spaced points along said second marginal portion, said clamping members being adapted to be held on said marginal portions against said respective edges by the inherent resilience thereof, said clamping members each including a first arm adapted to rest on said top and a second arm having an inwardly directed free end adapted to engage the lower surface of said marginal portion and about which the respective said clamping members can be tilted for applying said clamping members to their respective said marginal portions, a first holding member secured to said first arms of said first named certain clamping members, a second holding member secured to said first arms of said certain other clamping members, said holding members and said channel members being so related that, when said clamping members are disposed along their respective marginal portions, said holding members will be disposed parallel to the respective ones of said edges, a first partition mounted on one of said holding members, and a second partition mounted on the other of said holding members, said partitions being so disposed in said holding members as to also substantially meet at said corner, and said partitions each being of a height to afford a substantial degree of privacy for said top.
